UNITED STATES PATENT OFFICE

169,225

FUR SCARF OR SIMILAR ARTICLE

Sidney Ringler, Forest Hills, N. Y., assignor to Sidney Ringler Fur Co., Inc., New York, N. Y., a corporation of New York

Application November 13, 1952, Serial No. 22,248

Term of patent 14 years

(Cl. D3—2)

To all whom it may concern:

Be it known that I, Sidney Ringler, a citizen of the United States, residing at Forest Hills, in the county of Queens and State of New York, have invented a new, original, and ornamental Design for a Fur Scarf or Similar Article, of which the following is a specification, reference being had to the accompanying drawing, forming part thereof.

In the drawing:

I claim:

The ornamental design for a fur scarf or similar article, substantially as shown.

SIDNEY RINGLER.
